Inventor:
Alvan Macauley

By Milton Tibbats

UNITED STATES PATENT OFFICE.

ALVAN MACAULEY, OF DETROIT, MICHIGAN, ASSIGNEE TO PACKARD MOTOR CAR COMPANY, OF DETROIT, MICHIGAN, A CORPORATION OF MICHIGAN.

HYDROCARBON MOTOR.

Application filed May 10, 1919. Serial No. 896,268.

To all whom it may concern:

Be it known that I, ALVAN MACAULEY, a citizen of the United States, and resident of Detroit, Wayne County, State of Michigan, have invented certain new and useful Improvements in Hydrocarbon Motors, of which the following is a specification.

This invention relates to hydrocarbon motors and particularly to means for heating the explosive mixture prior to its admission into the cylinders.

The objects of the invention are to provide means for controlling the flow of the mixture against a hot surface so as to thereby enable the heating effect to be obtained or not as desired, or the temperature of the mixture regulated within certain limits, to provide a construction whereby the above controlling and regulating means are not

affected by the heat of the exhaust passage, and to provide means whereby any unvaporized particles of the liquid fuel that may be carried past the heating surface will fall back into the heated space so as to be thoroughly vaporized before the mixture passes into the cylinders.

With these objects in view, the invention is embodied in preferable form in the construction and arrangement hereinafter described and illustrated in the accompanying drawings in which Fig. 1 is an end elevation partly in vertical section of a hydrocarbon motor showing a form of my invention applied thereto, and Fig. 2 is a cross section on the line 2—2 of Fig. 1.

Referring to the drawings, 10 is a carburetor and 11 is a mixture conveying pipe section leading therefrom. This section in the embodiment here shown is preferably horizontal and joins a vertical section 12 constituting a conduit leading to an intake manifold 13 from which the explosive mixture is adapted to be distributed to the different cylinders of an internal combustion engine.

Substantially opposite the inner termination of the bore of the pipe section 11, the vertical pipe 12 is provided with an enlarged pocket 14 the bottom of which is slightly concave but which is above the level of the bottom of the pipe 11. This pocket formation enters into the interior space of a vertical pipe section 15, forming a continuation of the exhaust passageway and leading from a section 16, shown as extending across the

vertical axis of the motor and connected to the vertical branch 17 of an exhaust manifold 18. The vertical section of the exhaust passage extends substantially parallel to the bore of the intake section 12 and terminates in an exhaust outlet pipe 19. The exhaust pipe section 15 is cut away or formed to provide a chamber therein adjacent to the wall of the vertical intake section and thus a considerable area of the intake section will be subject to the effect of the hot gases, thus providing a heating surface of considerable area opposite and above the bore of the conduit 11 and providing a heated space within the pocket 14, whereby unvaporized parts of the mixture coming from the carburetor will be vaporized by contact with the heated surface and the resulting vapor carried forward into the manifold.

At high speeds of the engine the contact of the mixture with this heating surface will produce an excessive and undesirably high temperature of the vapor before its entrance into the cylinders. In order to avoid this objection means are provided for controlling the admission of the mixture to the heated space, consisting preferably of a valve such as indicated at 20 which is adapted to cut off communication between the pipe 11 and the pocket 14 or to admit the mixture to the space or to regulate the proportion of the parts of the mixture passing through the space, and directly up the vertical intake pipe. The valve may be controlled in any suitable manner. A link 21 and rod 22 are shown as the connecting means between the valve and any source of valve operating power.

A partition wall 23 may be continued upward within the pipe 12 from the pivot of the valve 20 in order to insure the proper diversion or separation of the mixture in accordance with the position of the valve.

In the operation of the device, the mixture will be drawn through the pipe 11 into the section 12 and if the valve 20 is open, as will be the case when the engine is started, the mixture will be carried against the heated wall of the pocket 14 owing to the deflection of the gases produced by the angular position of the valve.

The greater inertia of the unvaporized liquid particles of the fuel will aid in carrying them against the heated wall of the pocket opposite the end of the horizontal

pipe, while the lighter vaporized particles will be carried directly up the vertical pipe. The unvaporized particles that may be drawn into the vertical pipe 12 above the hot spot 5 will drop back by gravity into the pocket 14 and be there vaporized. The valve 20 is adapted to be closed or partly closed to cut off the admission of the mixture to the heating space or decrease the amount admitted 10 thereto when the engine has acquired sufficient speed to cause the cylinders to be heated, so that the additional heating effect in the intake will be unnecessary.

Having thus described my invention, what 15 I claim and desire to secure by Letters Patent is:

1. The combination with a hydrocarbon motor having an intake conduit and an exhaust conduit, of a mixture conveying pipe 20 below the intake conduit, a constantly upwardly extending conduit from said pipe to

the intake conduit, a second upwardly extending conduit from said pipe to the intake conduit, said second conduit being in heating relation to the exhaust conduit and having a vaporizing pocket therein, and a valve for directing the mixture from the pipe to either of said upwardly extending conduits. 25

2. The combination with a hydrocarbon motor, having intake and exhaust conduits, 30 of a mixture conveying pipe below the intake conduit, two conduits extending substantially in parallel constantly upwardly from said pipe to the intake conduit, one of said upwardly extending conduits being in heating relation to the exhaust conduit and having a vaporizing pocket therein, and a valve for directing the mixture from the pipe to either of said upwardly extending conduits. 35

In testimony whereof I affix my signature.

ALVAN MACAULEY.
